UNITED STATES PATENT OFFICE.

JOHN R. O'DONNELL, OF BROOKLYN, NEW YORK.

REINFORCED-CONCRETE FLOOR STRUCTURE.

1,217,985.

Specification of Letters Patent.

Patented Mar. 6, 1917.

Application filed June 23, 1916. Serial No. 105,331.

To all whom it may concern:

Be it known that I, JOHN R. O'DONNELL, a citizen of the United States, residing in the borough of Brooklyn, city of New York, county of Kings, and State of New York, have invented new and useful Improvements in Reinforced-Concrete Floor Structures, of which the following is a specification.

The invention relates to reinforced concrete flat slab floor structures and more particularly to that type wherein hollow blocks of terra cotta, gypsum, or some other material of greater compressive value than concrete, are incorporated as structural members and fillers between reinforced concrete beams. The object is to secure the greatest advantage in the use of such blocks for compression, and thereby to secure a stronger floor with less dead weight or to permit the construction of longer spans than heretofore. This is accomplished by a combination of reinforced concrete beams and intervening blocks of the character indicated, the blocks having thickened slab portions, which in the central or major part of the span are disposed at the top, while at and near the supports the blocks are inverted, their slab portions being at the bottom, to take care of negative compression, which exists at these regions and which may be much greater than the positive compression elsewhere. By this construction I eliminate a large amount of useless concrete which ordinary flat slab floors are required to carry at the bottom, at the center of the span, and at the top, over and adjacent the columns, thereby lightening the floor and avoiding the severe local stresses which result from such dead weight, and at the same time I insure sufficient material for compression at the places where it is needed, all of this being accomplished by the form of the blocks and, more especially, by the use of blocks of one kind, which merely require to be inverted at the points where the compression changes.

In the accompanying drawings illustrating the invention:

Figure 1 is a vertical section through a floor span constructed in accordance with the invention;

Fig. 2 is a perspective plan view of a section of the floor constructed on a two-way system.

Structural members carrying the floor

and marking the ends of the span are indicated at *a*. The concrete beams *b* are preferably arranged on a two-way system, that is to say, running at right angles to each other, with the spaces between them rectangular, though this is not essential. The spaces between beams are filled by hollow, open-end terra cotta blocks *c*, the characteristic of which is not only that they have one greatly thickened wall *d* forming a heavy slab portion, the opposite wall being of ordinary thickness or relatively thin, but that in the central part of the span this slab portion of the blocks is at the top while toward the supports it is at the bottom, the inversion of the blocks occurring at points corresponding approximately to a change in compression from positive to negative, that is to say, from the upper to the lower part of the floor. For simplicity the blocks are referred to as of terra cotta, but it will be understood that gypsum or other suitable, equivalent material may be used. In the part of the floor where the blocks have their slabs at the top the reinforcements *e* are in the lower portions of the beams, while near the supports the reinforcements may be reversed in position correspondingly to the slabs.

What I claim as new is:

1. A flat slab reinforced concrete floor comprising reinforced concrete beams with hollow blocks between the beams, said blocks having thickened heavy slab portions at one side of the central horizontal plane, the blocks in the central part of the span having their slab portions at the top and those near the supports being inverted with their slab portions at the bottom.

2. A composite floor composed of hollow blocks and reinforced concrete forming a flat slab, the blocks comprising an identical form having one thickened heavy slab portion, the said blocks being relatively inverted in different parts of the slab, those in the central portion having their thickened slab portions at the top and those over the supports having their slab portions at the bottom.

Dated this 22nd day of June, 1916.

JOHN R. O'DONNELL.
